FLEXIBLE DOLL HEAD WITH EYE SET, AND
EYE SET SUPPORT MEANS THEREFORLeo J. Grubman, Belle Harbor, N. Y., assignor to
Margon Corporation, New York, N. Y., a cor-
poration of New York

Application November 4, 1932, Serial No. 641,164

20 Claims. (Cl. 46—40)

This invention relates to dolls, and more particularly to flexible doll heads provided with eye sets, and also relates to eye set support means for such heads.

Flexible doll heads molded, for example, out of rubber, have proved popular because of their better simulation of the yieldability of natural flesh. Such heads, however, have not commonly been provided with movable eye sets such as are regularly employed on the more expensive or better varieties of rigid head. This is so because of numerous and manifest difficulties which arise in connection with flexible heads, due largely to the flexible and readily deformable nature of the head. It is difficult, for example, to establish a fixed or desirable spacial relation between eye set support means and the eye sockets or eye openings in a rubber head because the eye openings are readily distorted by deformation of other parts of the head. Furthermore, I have found that a change in shape, or deformation of the eye opening, takes place as the rubber of the head ages, for a certain sagging or sinking of the material seems to occur in the course of time. Accordingly, one primary and important object of the present invention is to overcome the foregoing difficulties and to reinforce the eye openings of the head, so that despite the flexibility and yieldability of the head as a whole, the eye openings themselves will permanently retain their initial shape and dimension. The reinforced eye openings are designed not only to resist externally applied stress, but also to obviate any change in shape caused by sagging or sinking of the material of the head with passage of time. Another important and practically self-evident difficulty which arises when attempting to equip flexible heads with movable eyes, is to provide appropriate supporting means for mounting the eye set in the head. The problem is difficult of solution even in the case of a rigid head, because allowance must be made for extremely rough handling and abuse of the head, and, in the case of a flexible head, these difficulties are greatly multiplied. Accordingly, another primary object of the present invention resides in the provision of suitable support means for mounting an eye set in a doll head, particularly a flexible or rubber doll head. Ancillary objects of my invention considered in this aspect are not only to fulfil the desiderata of strength, economy, and ease of attachment of the eye set, but also the maintenance of a fixed spacial relation between the center of oscillation of the eye set and the eye openings. By accurately maintaining the

desired spacial relation, a predetermined slight clearance may be established which permits free and frictionless operation of the eye set. This is particularly desirable in the case of a rubber head because a spring action between the support means and the eye set requires excessive spring pressure, with increase in contact friction, if the eye set is to be kept in proper contact with the eye openings despite deformation of the kind occurring in a flexible head. This increase in friction is not desirably overcome by the use of a heavier operating weight because such weight, if excessive, itself tends to pull the eye set away from the eye openings. It will be apparent that the present invention, by first reinforcing and rigidifying the eye openings, and by secondly establishing a fixed and dependable relation between the eye set and the eye openings, avoids the foregoing difficulties and establishes conditions not only comparable to but in some respects actually superior to those existing in the case of a rigid head.

The eye openings are preferably reinforced by the use of socket plates embedded in the material of the head when molding the same; and further objects of my invention are, first, to make a given size and type of socket plate suitable for use with several sizes of head; and secondly, to adapt such socket plates for use both when the eye openings are to be permitted relative movement, and when the eye openings are to be reinforced and rigidified relatively as well as individually. Still further objects of the present invention are to provide for supporting the eye set by either outer or inner or central bearings, as desired, or both outer and inner bearings supporting each eye member adjacent the mating eye opening, and, in the latter case, when relative movement of the eye openings is permitted, to provide for yieldability of the connection between the operating weight and the eye members.

To the accomplishment of the foregoing and such other objects as will hereinafter appear, my invention consists in the flexible head and reinforcing and eye set supporting elements, and their relation one to the other, as hereinafter are more particularly described in the specification and sought to be defined in the claims. The specification is accompanied by drawings, in which:

Referring to the various forms of invention shown in the drawings, the head H is molded out of a moldable material, preferably a flexible material such as rubber, and is provided with a movable or oscillatable eye set E fitting in eye openings formed in the head. The eye opening is in each case reinforced by an appropriate reinforce plate P having a main opening concentric with the eye opening and embedded or molded directly inside of the front wall of the head. The opening in the reinforce plate P may, of course, be made equal to the eye opening but is preferably made larger than the eye opening, first, to increase manufacturing tolerance in registering the same; secondly, to avoid exposing the metallic edge of the reinforce plate; and third, to make a given size of reinforce plate suitable for a range of size of doll head. The difference in spacing between the eyes in different size heads may be accommodated by using separate reinforce plates, as in the arrangements of Figs. 8, 13, and 14, or, if it is preferred to rigidly interconnect the plates so as to prevent relative movement of the eye openings, the plates are interconnected by using a separate connecting piece C spot welded to the reinforce plates, as shown in Figs. 2 and 17, for example. It will be evident, without additional comment, that the reinforce plates P prevent the eye openings from being squeezed out of shape by deformation of the head, and further that any sag or change in shape or dimension of the head, due to aging of the rubber, will not result in changing the eye openings themselves.

The various modifications of the invention are further generically characterized by the fact that in each case the eye set E is supported in desired and predetermined spacial relation to the eye openings by support means S formed integrally with or rigidly attached to the aforesaid reinforce plates P. This mode of support obviously fixes and maintains the spacial relation between the eye set and the eye opening and, besides solving the problem of maintaining this spacing, it incidentally but very importantly solves the problem

of providing suitable support means for mounting an eye set in a doll head even when the head is molded of flexible rubber.

Considering the first form of my invention in greater detail, and referring to Figs. 1, 2, and 3 of the drawings, the head H is molded out of flexible rubber in a one-piece molding operation, in accordance with known practice. The eye set E may be of conventional type comprising a cross rod 12 carrying eye members 14 and a depending weight 16. The reinforce plates P are stamped out of sheet metal and are so shaped and dimensioned as to fit within the head wall around the eye openings 18 of the head. This necessitates an outward dishing or concavity of the plates, as will be evident from an inspection of Fig. 1, and even more clearly evident by reference to Fig. 18. Each plate is provided with a main opening 20 which is preferably somewhat larger than the eye opening 18. Each plate is preferably further provided with smaller locating openings 22. These openings are designed to mate with locating pins formed on the core of the mold, which pins insure proper location of the reinforce plates and proper concentricity of the openings 18 and 20. Additional holes may be provided in the reinforce plates permitting the material of the head to flow therethrough during the molding operation, in order to improve the security with which the plate is anchored in the head, and in order to bind together the sides of the wall on opposite sides of the plate.

The reinforce plates P are interconnected by connecting means C extending therebetween and affixed thereto, as by spot welding. In the present case the connecting means C consists of an H-shaped member extending horizontally between the reinforce plates. The general arrangement will be apparent from an inspection of Figs. 17 and 18, showing reinforce plates P interconnected by a horizontally positioned H-shaped member C. Reverting to Fig. 2, the ends 26 of the H-shaped member straddle the openings 20 and are spot welded to the top and bottom of the reinforce plates. The space between the ends 26 is preferably formed by striking and rearwardly bending the metal to form the rearwardly extending support arms S. The support arms are thus integral with the connecting member C which in turn is rigidly affixed to the reinforce plates P.

It will be noted that the head H includes ribs or webs 28 extending vertically above the support arms S. These webs are formed by grooves cut in the core about which the head is molded. The support arms S of the complete fitting rest in one end of the grooves. When the head is removed from the core, advantage is taken of the resilient nature of the material of the head, it being seized at the neck opening and pulled or rolled backwardly from the core. Grooves such as I am now mentioning, facilitates stripping the head from the core because they permit the metal arms S to slide rearwardly from the core, instead of necessitating that the head be stretched outwardly sufficiently to extract the arms from small recesses in the core. These grooves, which are primarily intended to facilitate removal of the molded head from the core, incidentally produce the webs 28 which in turn prove of advantage in reinforcing the forehead of the doll and providing a resistance to deformation at that point.

The arms S are preferably slotted or bifurcated, as is indicated at 30, to receive the cross rod 12 of the eye set. The cross rod may be retained in the slot 30 in a number of ways, that shown

in Figs. 1, 2, and 3 involving the use of a frame-like rectangular clip 32 made of spring metal and bent into V shape, as is best shown in Fig. 3. Arms S are notched at 34 and tapered at 36 so that the clip 32 may be slipped over the pair of arms behind the cross rod and pushed forwardly until it snaps into notches 34. The end of web 28 is thin and readily moved aside by the clip.

An alternative way to anchor the cross rod in slot 38 of arm S is shown in Figs. 4 and 5, referring to which it will be seen that the cross rod 12 is held in place by a housing clip 38 which surrounds the arm S with a tight frictional fit and which is itself slotted, as indicated at 40, to mate with slot 38. It will be evident that it is simply necessary to push a clip 38 over each of the arms S after the eye set has been placed in slots 38.

Still another method for holding the cross rod 12 on arms S is shown in Figs. 6 and 7 of the drawings, referring to which it will be seen that the arms are notched at 42 and that the cross rod is held in slots 38 by a spring clip 44 which is generally U-shaped, when viewed in plan, and the ends of which are provided with hooks or detent lugs 46 which are received in notches 42 and which hold the clip on the arms S. The sides 48 of clip 44 may be slotted or bifurcated, as is indicated at 50 in Fig. 6, in order to fit around the cross rod 12. This, however, depends simply upon the relative dimensioning of the arms and notches therein with the clip and the desired spacing of the cross rod.

The cross rod may be held on the arms S by retaining lugs formed integrally with the arms, instead of by using separate clips such as have thus far been described. Such an arrangement may be described in connection with Figs. 17, 18, and 19 of the drawings, and referring thereto the reinforce plates P correspond to those heretofore described and are interconnected, as by spot welding, with a horizontally positioned H-shaped connecting member C which in turn has integrally formed therewith rearwardly extending support arms S. The support arms S are slotted at 52 to receive the cross rod 12 of the eye set. This slot, however, instead of being open-ended, is obstructed by a retaining lug 54, best shown in Fig. 19. The retaining lugs 54 may initially be bent downwardly to clear the slot 52, in the manner shown in Figs. 17 and 18. If desired, the lugs 54 may be left in the normal position shown in Fig. 19 during the molding operation, and may subsequently be bent sufficiently to clear the cross rod, and then restored to a position retaining the cross rod in place. In either case an integral part of the support arm S is arranged to hold the cross rod in place but is not in the way when first inserting the cross rod in the support arm.

Another form of my invention is illustrated in Figs. 8, 9, and 10 of the drawings. This form of the invention is similar to that heretofore described, in that reinforce plates P are used at each of the eye openings; but differs importantly in that the reinforce plates P are not interconnected by a connecting member, but instead are left separate and relatively movable. In other words, while each eye opening in head H is reinforced against distortion, shrinkage, and the like by its associated reinforce plate P, no attempt is made to prevent relative displacement of one eye opening with respect to the other.

The reinforce plates P may be appropriately shaped in any desired manner, those here illustrated being approximately square in outline.

The plates are each provided with a main opening 28 which, as has already been explained, is preferably somewhat larger than the eye opening 18. Each plate is further provided with smaller openings 22 one or more of which may be used as locating holes for cooperation with locating pins on the molding core, and remaining ones of which may be used as anchor holes through which the rubber material of the head is permitted to flow. The reinforce plates P are provided with rearwardly extending support arms S which in the present case are triangular in shape, as is best shown in Fig. 10. The support arms are provided with means for receiving and supporting the cross rod 12 of eye set E, and in the present case the support means consists simply of bearing holes 66 punched through the support arm. The support arms S in the present instance form end bearings for eye set E, and for this purpose are located at the outermost or remote edges of the reinforce plates P. To mount the eye set in place, it is simply necessary to stretch the support arms S widely apart, as by stretching apart the sides of the head, until the ends of the cross rod are brought into the bearing holes 66. The cross rod is preferably made substantially longer than the distance between the support arms S, so that when once mounted in place it will be extremely difficult to dislodge the same from its mounting. This elongation of the cross rod does not prevent the same from being mounted in the head, because advantage may be taken of the flexible nature of the head to sufficiently stretch the same for the desired purpose. In passing, it may be noted that the interior front wall of the head may be provided with ribs or webs 28 aligned with support arms S and corresponding to the webs 28, the cause and purpose of which were already pointed out in connection with Figs 1 and 2 of the drawings.

Another form of the invention is illustrated in Figs. 11, 12, and 13, referring to which the reinforce plates P resemble those last described in that they are separate from one another, and also by reason of the fact that the support arms S are formed integrally with and bent rearwardly from the plates P. The present form, however, differs in that the support arms are located at the inner or adjacent edges of the reinforce plates and constitute center bearings for the eye set E.

The support plates P in the present case are each preferably semi-elliptical in outline, the straight or diametrical edges being arranged toward one another and forming the fold line of the support arms S. These are preferably bifurcated to form a receptive slot 70 the edges of which are notched, as is indicated at 72. The width of material is reduced somewhat at the point 74 so that the metal at either side of slot 70 may be spread, as indicated in Fig. 12, or closed, as indicated in Figs. 11 and 13. In order to hold the cross rod 12 of the eye set in place, a key 76 is employed the construction of which is evident from the perspective view in Fig. 12. After the eye set has been placed in slot 70, the key 76 is also placed in the slot at the notches 72, and the spread arms are thereupon squeezed together by any appropriate tool, thereby permanently locking the parts in assembled relation. In connection with this form of the invention, it will be noted that the head is provided with webs 28 aligned with support arms S and corresponding to those heretofore described. It will also be

noted that the reinforce plates P are provided with holes 22 which may be used as locating holes, or anchorage holes, or partially as either. In this case, as in the case of the arrangements already described, it will be appreciated that the location of the reinforce plates, when molding the head, is only partially maintained by the locating holes, for much of the support for the insert, particularly in a transverse direction, is obtained by reason of the support arms S being located in and supported by the mating groove in the core of the mold.

Attention is next directed to the form of the invention illustrated in Figs. 14, 15, and 16. This form of the invention corresponds to those last described in that separate reinforce plates P are used. It differs by employing support arms S at both the inner and outer edges of the support plates, thereby providing both central and end bearings for the eye set. This in turn is divided into two parts which are respectively and independently supported by the reinforce plates. The two parts of the eye set are connected to a common weight, but in so flexible a manner that relative movement of the eye openings and with them the halves of the eye set is permitted without injury or bending of any of the parts.

Considered in greater detail, the reinforce plates P are preferably made similar and interchangeable, and each includes support arms S bent rearwardly from both sides of the support plate. The support plate is preferably made of resilient metal so that the arms S may be spread apart to receive the short or stub shafts 112. These individual shafts or cross rods are preferably reduced at the ends, as indicated at 114, thereby forming shoulders which act as thrust bearings contacting with the inner surfaces of the arms S. It is not essential to use such shoulders, for the shaft may be lengthened slightly and reliance placed upon the mating fit of the eye shell and eye opening to hold the shaft against axial movement. Each shaft 112 carries an eye shell 114 which in turn is oscillated by a key 116 located partially within and partially in back of the eye shell and frictionally secured to the shaft 112 in a manner best shown in Fig. 16. Weight wires 118 and 120 are secured to keys 116. Weight wire 120 carries a common operating weight 122 and is appropriately bent to bring the weight approximately centrally between the eye members. Weight wire 118 is provided with a loop or eyelet 126 which somewhat loosely surrounds the weight wire 120. It will be evident on inspection of the drawings that with the arrangement here shown, each eye shell is spacially related to its eye opening in a precise manner, and this relation is undisturbed regardless of how much the flexible head may be squeezed or distorted out of shape. Equal and simultaneous movement of the eye members is insured by operating the same through a single or common operating weight, yet the connection of the eye members to the common weight is arranged for flexibility or universal movement, so that no injury is caused the eye set by deformation of the head, and, in fact, except for very extreme abuse, the eye set will actually continue to operate in a satisfactory manner even though the eye openings are displaced one relative to another.

It is believed that the mode of constructing and using doll heads made in accordance with my invention, and the many advantages thereof, will, for the most part, be apparent from the foregoing

detailed description. The invention is particularly applicable to flexible heads made, for example, of rubber, and in such case the eye openings are reinforced against forceful deformation or gradual change in shape upon aging of the rubber. The eye set is supported directly from the eye opening reinforcement in a simple, dependable and satisfactory manner, and the nature of the support predetermines the spacial relation between the eye set and the eye openings. Considered in this aspect, the invention is, of course, applicable to and valuable in connection with heads made of molded material even though not flexible. The reinforce plates may be rigidly interconnected by metal, or may be left relatively movable in the head. When interconnected by metal, a standardized reinforce plate may be used for a range of head size or range of spacing between eye openings. Provision is made for proper location of the reinforce plates during the molding operation, and for stripping of the molded head from the core of the mold. The eye set may be of exceedingly simple type consisting merely of a conventional cross rod carrying eye members and an operating weight. This eye set may be supported by end bearings, or center bearings, or both. In the last case the eye members may, if desired, be separately pivoted and relatively movable with the eye openings, the eye members being operated by a common operating weight so connected to the eye members as not to interfere with relative movement thereof. The eye set is added to the head after completion of the molding operation, by passing the same through the neck opening of the head and attaching the same in place in a variety of ways involving, for example, the use of spring clips, or interlocking members, or bendable retaining lugs, or, even more simply, by temporary spreading of the support arms to receive the eye set.

It will therefore be apparent that while I have shown and described my invention in preferred forms, many changes and modifications may be made in the structures disclosed, without departing from the spirit of the invention, defined in the following claims.

I claim:

1. An eye socket reinforcing fitting adapted to be molded in a doll head made of flexible molded material, said fitting comprising an eye socket reinforcing plate having a main opening larger than the eye socket around which it is to be placed, and smaller holes in the plate outside of said opening, said plate being generally flat but shaped and dimensioned to fit within the head wall at the eye opening with its surface lying parallel to but within the wall.

2. An eye set supporting fitting adapted to be molded in a doll head made of rubber, said fitting comprising an eye socket reinforcing plate having a main opening larger than the eye socket around which it is to be placed, smaller holes located outside the main opening, and support means including a rearwardly extending arm fixed to said socket plate and provided with means for receiving and supporting the shaft or cross rod of an oscillatable eye set, said plate being generally flat but shaped and dimensioned to fit within the head wall at the eye opening with its surface lying parallel to but within the wall.

3. A flexible doll head made of rubber and provided with eye socket reinforcing means molded in the front wall of the head, said means comprising eye socket reinforcing plates molded in the front wall of the head and surrounding said eye

opening, each of said plates being generally flat and shaped to lie parallel to the wall within which it is molded, and having an opening the edge of which surrounds the eye opening of the head.

5. A doll head made of rubber and provided with eye socket reinforcing means molded in the front wall of the head, said means comprising eye socket reinforcing plates molded in the front wall of the head and each having a main opening larger than the eye opening and surrounding said eye opening, and smaller holes in said plate outside of said main opening, said plates being generally flat but shaped and dimensioned to fit within the head wall at the eye openings, with the surfaces of the plates lying generally parallel to but within the wall.

10. A doll head made of rubber and provided with an eye set, and with eye set supporting means molded in the front wall of the head, said means comprising a sheet metal member molded in the front wall of the head, said member being generally flat but shaped and dimensioned to fit within the head wall at the eye opening, with the surface of the member lying parallel to but within the wall, and an eye set support arm extending rearwardly from said member, said eye set being mounted in and supported by the aforesaid support arm.

15. A doll head made of flexible moldable material provided with an eye set and with an eye socket reinforcing and eye set supporting means molded in the front wall of the head, said means comprising eye socket reinforcing plates molded in the front wall of the head and having openings larger than the eye openings and surrounding said eye openings, said plates being generally flat but shaped and dimensioned to fit within the head wall at the eye openings, with the surfaces of the plates lying parallel to but within the wall, and eye set support arms extending rearwardly from said reinforcing plates, said eye set being mounted in and supported by the aforesaid support arms.

20. A doll head made of rubber and provided with an eye set and with an eye socket reinforcing and eye set supporting means molded in the front wall of the head, said means comprising eye socket reinforcing plates molded in the front wall of the head and each having a main opening corresponding to the eye opening and surrounding said eye opening, smaller holes located outside of the main opening, said plates being generally flat but shaped and dimensioned to fit within the head wall at the eye openings, with the surfaces of the plates lying parallel to but within the wall, and eye set support arms extending rearwardly from said reinforcing plates, said eye set being mounted in and supported by the aforesaid support arms.

25. An eye socket reinforcing and eye set supporting means adapted to be molded in a doll head, said means including socket plates interconnected by a connecting member arranged between said socket plates, support arms for an eye set extending rearwardly from said member, each of said socket plates having an opening corresponding to the eye opening in the head, and said socket plates and connecting member being generally flat but shaped and dimensioned to fit in the front wall of the head with its surface lying parallel to but within the wall.

30. An eye socket reinforcing and eye set supporting means adapted to be molded in a flexible rubber doll head, said means including socket plates interconnected by an H-shaped connect-

ing member arranged horizontally between and secured to said socket plates, the center metal of said connecting member being bent rearwardly to form support arms for an eye set, each of said socket plates having an opening larger than the eye opening in the head, and said socket plates and connecting member being generally flat but shaped and dimensioned to fit in the front wall of the head with its surface lying parallel to but within the wall.

35. A flexible rubber doll head having integral- 5
ly molded therein eye socket reinforcing and eye set supporting means, said means including socket plates interconnected by a connecting member arranged between said socket plates, support arms for an eye set extending rearwardly from said assembly, each of said socket plates having an opening surrounding the eye opening in the head, said socket plates and member being molded in the front wall of the head, said plates being generally flat but shaped and dimensioned to fit within the head wall at the eye openings, with the surfaces of the plates lying generally parallel to but within the wall, and an eye set supported by said support.

40. A flexible rubber doll head having integral- 10
ly molded therein eye set supporting means, said means including an H-shaped member arranged horizontally between the eye openings of the head, the center metal of said member being bent rearwardly to form support arms for an eye set, said member being molded in the front wall of the head, and being generally flat but shaped and dimensioned to fit within the head wall at the eye opening, with the surface of the member lying parallel to but within the wall, except for the support arms, and an eye set including a shaft having a pair of eye members and a depending gravity weight mounted thereon, and means on said support arms for receiving and holding the eye set in place.

45. A flexible rubber doll head having integral- 15
ly molded therein eye socket reinforcing and eye set supporting means, said means including socket plates interconnected by an H-shaped connecting member arranged horizontally between and secured to said socket plates, the center metal of said connecting member being bent rearwardly to form support arms for an eye set, each of said socket plates having an opening surrounding the eye opening in the head, said socket plates and connecting member being molded in the front wall of the head, said plates being generally flat but shaped and dimensioned to fit within the head wall at the eye openings, with the surfaces of the plates lying generally parallel to but within the wall, and an eye set including a shaft having a pair of eye members and a depending gravity weight mounted thereon, and means on said support arms for receiving and holding the eye set in place.

50. A flexible doll's head including eye socket reinforcing and eye set supporting means molded directly therein, said means including a pair of separate socket plates each having an opening corresponding to the eye opening in the head and molded in the material of the head surrounding the said eye opening, said plates being generally flat but shaped and dimensioned to fit within the head wall at the eye openings, with the surfaces of the plates lying generally parallel to but within the wall, said plates further including rearwardly extending eye set supporting arms.

55. A flexible rubber dolls' head including eye 70
75

- socket reinforcing and eye set supporting means molded directly therein, and an eye set, said means including a pair of separate socket plates each having an opening larger than the eye opening in the head and molded in the material of the head surrounding the said eye opening, said plates being generally flat but shaped and dimensioned to fit within the head wall at the eye openings, with the surfaces of the plates lying generally flat but shaped and dimensioned to fit within the head wall at the eye openings, with the surfaces of the plates lying generally parallel to but within the wall, said plates further including rearwardly extending eye set supporting arms, and an eye set supported by said arms, said arms being located at the inner and outer sides of said plates and constituting center and end bearings for said eye set.
10. A flexible doll's head including eye socket reinforcing and eye set supporting means molded directly therein, said means including a pair of separate socket plates each having an eye opening and molded in the material of the head surrounding the said eye opening, said plates being generally flat but shaped and dimensioned to fit within the head wall at the eye openings, with the surfaces of the plates lying generally parallel to but within the wall, said plates further including rearwardly extending eye set supporting arms, and an eye set supported by said arms, said arms being located at the outer sides of the plates and constituting end bearings for the eye set.
15. A flexible doll's head including eye socket reinforcing and eye set supporting means molded directly therein, said means including a pair of separate socket plates each having an eye opening and molded in the material of the head surrounding the said eye opening, said plates being generally flat but shaped and dimensioned to fit within the head wall at the eye openings, with the surfaces of the plates lying generally parallel to but within the wall, each of said plates further including a pair of rearwardly extending support arms formed integrally with said plate at each side thereof, and an eye set supported by said arms, said eye set including a pair of shafts one located in the support arms of each of the plates, an eye shell on each of said shafts, a weight, and means so interconnecting the eye shells and weight as to permit relative movement of the plates and eye shells when the head is deformed.
20. A flexible doll's head including eye socket reinforcing and eye set supporting means molded directly therein, said means including a pair of separate socket plates each having an eye opening and molded in the material of the head surrounding the said eye opening, said plates being generally flat but shaped and dimensioned to fit within the head wall at the eye openings, with the surfaces of the plates lying generally parallel to but within the wall, said plates further including rearwardly extending eye set supporting arms, and an eye set supported by said arms, said arms being located at the outer sides of the plates and constituting end bearings for the eye set.
25. A flexible doll's head including eye socket reinforcing and eye set supporting means molded directly therein, said means including a pair of separate socket plates each having an eye opening and molded in the material of the head surrounding the said eye opening, said plates being generally flat but shaped and dimensioned to fit within the head wall at the eye openings, with the surfaces of the plates lying generally parallel to but within the wall, each of said plates further including a pair of rearwardly extending support arms formed integrally with said plate at each side thereof, and an eye set supported by said arms, said eye set including a pair of shafts one located in the support arms of each of the plates, an eye shell on each of said shafts, a weight, and means so interconnecting the eye shells and weight as to permit relative movement of the plates and eye shells when the head is deformed.
30. A flexible soft rubber doll head including eye sockets, metallic stiffening and reinforcing means molded in the wall of the head, at least a part of said means being located near the eye socket portion of the head, and substantially all of said means being embedded within and concealed by the rubber material of the head wall, and eye members movably supported at and exposed by said eye sockets.
35. A flexible soft rubber doll head including eye sockets, metallic stiffening and reinforcing means molded in the front wall of the head, said means being larger than and located around the eye socket portion of the head and being embedded within and covered on both sides by the rubber material of the head wall, and eye members movably supported at and exposed by said eye sockets.
40. A flexible soft rubber doll head including eye sockets, metallic stiffening and reinforcing means molded in the front wall of the head, said means being larger than and located around the eye socket portion of the head and being embedded within and covered on both sides by the rubber material of the head wall, and eye members movably supported at and exposed by said eye sockets.
45. A flexible soft rubber doll head including eye sockets, metallic stiffening and reinforcing means molded in the front wall of the head, said means being larger than and located around the eye socket portion of the head and being embedded within and covered on both sides by the rubber material of the head wall, and eye members movably supported at and exposed by said eye sockets.
